[57] **ABSTRACT**

A protective covering is provided for a tensioned cable encircling a concrete tank. The covering is in the form of a tube having its opposite ends in a frame mounted on the tank. After the cable is prestressed, grout is poured into one end of the tube to fill the annular space between the cable and tube for protection of the stressed cable against corrosion and vandalism.

PROTECTIVE ARRANGEMENT FOR EXPOSED TENSIONED CABLE

The present invention relates to means and techniques useful in the protection of tensioned cable against corrosion, vandalism and other outside influences.

Oftentimes in the repair and reinforcement of prestressed concrete tanks, it is desirable to add reinforcement in the nature of tensioned cables encircling such tank. Such tensioned cable is exposed and is subject to outside influence. One purpose of this invention is to provide a protective covering for the cable of such nature that it is protected against corrosion and is not subject to being snapped as a result of being hit by a high-velocity bullet.

It is therefore an object of the present invention to provide improved protection for tensioned cable to achieve the aforementioned purposes.

A specific object of the present invention is to provide a covering for a tensioned cable in the form of a tube encircling the cable with cementitious material filling the annular space between the cable and the outer tube.

Another specific object of the present invention is to provide protection of this character in which the tensioned steel is completely sealed off from the atmosphere.

Another specific object of the present invention is to provide an arrangement of this character which is suitable for replacement of corroded wires in circumferentially prestressed tank walls.

The features of the present invention which are believed to be novel are set forth with particularity in the appended claims. This invention itself, both as to its organization and manner of operation, together with further objects and advantages thereof, may be best understood by reference to the following description taken in connection with the accompanying drawings in which:

FIG. 1 is a front view showing a portion of a concrete circular wall with a protected reinforcing cable wound around it and apparatus mounted on such wall portion for terminating the ends of the cable and maintaining the same in tensioned protected condition.

FIG. 2 is a view taken in the direction indicated by line 2-2 in FIG. 1.

FIG. 3 is a sectional view taken substantially on line 3-3 of FIG. 1.

FIG. 4 is a sectional view taken substantially on line 4-4 of FIG. 3.

FIG. 5 is a sectional view taken substantially on line 5-5 of FIG. 2.

An important feature of the present invention involves encasing the stressing cable 10 within a protective housing 12 with a hardened cementitious material 13 filling the space between cable 10 and housing 12. This is accomplished using the structure now described.

An elongated supporting structure in the nature of a box frame 14 is secured to the circular wall W by a pair of bolts 16 at each end of frame 14. The frame 14 involves a welded construction in which there is a pair of end plates 14A, 14B, interconnecting elongated side plates 14C, 14D, and three braces 14E, 14F, 14G extending between and interconnecting plates 14C, 14D. As exemplified in FIG. 3, the base portion of the end

members, typified by end member 14A conforms with the surface of wall W and the outside planar surface of end member 14A is tilted somewhat instead of being perpendicular to the wall.

5 The ends of the protective housing 12 in the nature of a flexible metal tube are secured in the frame end members 14A, 14B respectively, as typified in FIG. 3, for example, by press or slip fitting the same in circular apertured portion 14K of end plate 14A.

10 Such fitting of the ends of tube 12 in frame end plates 14A, 14B is accomplished after the tube 12, with or without the cable 10 is initially wound around the tank. As illustrated, there is only one turn of housing or tube 15 12 around the wall, but the tube 12 may be wound to provide more than one turn after which its ends are secured as previously described.

15 The cable 10 is then threaded through the protective housing in those instances where the cable is not wound 20 as part of the tube assembly. In any case the ends of cable 12 project through the frame end plates 14A and 14B and are secured after tensioning or stressing of the cable by means typified and described now in connection with FIGS. 3 and 4.

25 Conventional cable anchoring devices are used in the nature of, for example, split conical wedge elements 20 slidably mounted in the complementary conical opening in sleeve like member 22. The sleeve member 22 is in contact with and is maintained spaced from the plate 30 14A by a pair of spaced segments 26 (FIGS. 3 and 4) which may be secured as, for example, by spotwelding to frame end plate 14A.

35 These end plates 14A, 14B also have secured to them end housing elements 14L and 14M respectively, each in the form of a cylinder having its outer end threaded to receive a nipple 25 within which is threaded a two-piece plug comprising an outer large plug 27 within which is threaded a smaller plug 28.

40 The cable is tensioned prior to mounting of the nipple 25 so as to allow access to the cable ends for tensioning purposes. After the cable tensioning operation, accomplished by the use of conventional apparatus involving the engagement and wedging of the clamping devices 20, 22 so as to maintain a tensioned condition

45 the excess protruding cable end or ends as the case may be are cut off and the nipple assemblies 25, 26, 28 are mounted preparatory to the introduction of grout to the interior of housing 12. For this latter purpose the plug 28 at each end is removed and grout under pressure is forced into one of the plug openings forcing air out of the other plug opening until completely filled. It will be seen that the split spacer 26, 26 at each plate

50 55 14A, 14B permits the flow of grout from within housing 14L into the tube 12 and from tube 12 into housing 14M to assure a complete filling of the annular space between tube 12 and cable 10.

While the particular embodiments of the present invention have been shown and described, it will be obvious to those skilled in the art that changes and modifications may be made without departing from the invention in its broader aspects and, therefore, the aim in the appended claims is to cover all such changes and modifications as fall within the true spirit and scope of this invention.

60 I claim:

1. In a precompressed cylindrical structure, a housing for tensioned cables including a frame structure incorporating two spaced abutments thereon; a tube encompassing the wall of the cylindrical structure with the ends of said tube being secured to a corresponding one of said abutments; a tensioned cable extending throughout the length of said tube and having opposite end portions thereof projecting out of said tube; a cable clamp on each of said end portions and cooperating with corresponding abutments to secure the same thereto; enclosure means secured to a corresponding one of said abutments and enclosing a corresponding one of said cable clamps and cementitious material filling said tube and said enclosure means.

2. A structure as set forth in claim 1 including spaced spacing means interposed between each of said cable clamps and the corresponding abutment whereby the material is uninterrupted from one of said enclosure

means through one of said spacing means, through said tube, through the other one of said spacing means and into the other of said enclosure means.

3. A structure as set forth in claim 1 in which said abutments comprises a pair of spaced plates, one at each end of said frame, said frame being elongated between said pair of plates.

4. A structure as set forth in claim 3 in which said plates are disposed in planes angularly related to each other and in convergent relation away from the longitudinal axis of said cylindrical structure.

5. A structure as set forth in claim 1 wherein means secure said frame structure to said cylindrical structure and end portions of said tube extend through said frame structure.

6. A structure as set forth in claim 1 in which at least one of said enclosure means includes a removable plug.
